UNITED STATES PATENT OFFICE.

JOHN E. LIMBACHER, OF ST. MARYS, OHIO.

OIL-BURNER.

1,242,567.

Specification of Letters Patent.

Patented Oct. 9, 1917.

Application filed January 18, 1917. Serial No. 142,124.

To all whom it may concern:

Be it known that I, JOHN E. LIMBACHER, a citizen of the United States, residing at St. Marys, in the county of Auglaize and State of Ohio, have invented certain new and useful Improvements in Oil-Burners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to new and useful improvements in oil burners, and consists more specifically in certain improvements in the oil burner shown and described in my former Patent No. 1,197,217 of September 5, 1916.

The object of the present improvements, is to provide an oil burner especially for boiler use, and in which steam is directed to the film of oil escaping from the oil discharge pipe to mix therewith in the preparation of the oil for combustion. The steam is directed through the contracted end of a pipe which incloses the oil pipe at the point where said pipe enters the furnace wall. From the discharge end of said steam pipe the steam passes through a series of jet openings immediately back of the point of the escaping film of oil, as will be hereinafter more fully described in connection with the accompanying drawings, of which Figure 1, is a horizontal sectional view of my improved oil burner: Fig. 2, is a vertical sectional view on the line 2--2 of Fig. 1: and Fig. 3, is a view of the discharge end of the burner.

In the accompanying drawings, similar reference characters indicate corresponding parts.

A represents the fire-brick wall of a furnace, within which is mounted a steam inlet pipe B having a contracted end C. This contracted end C is provided with a series of jet openings D which extend around the oil pipe or nozzle E immediately in the rear thereof. The steam pipe B is connected by

means of a T-fitting K to the lateral steam feed pipe F, the steam being controlled in its passage from pipe F to pipe B by a suitable valve G. The oil pipe or nozzle E is coupled to a continuation thereof to wit, pipes H and H' by means of a union I and T-fitting I', the latter being connected with the oil inlet pipe J having a controlling valve J'. The steam passage through the T-fitting K and pipe B is sealed by a packing gland L through which the oil pipe section H passes, and likewise the pipe section H' of the oil feed pipe is sealed by means of a packing gland L'. A feed rod M, extends through the connected oil pipes E and H and H', the outer end of which is equipped with a hand wheel N. The outer section H' of said pipe has a screw-threaded connection O, with the packing gland L', and by turning the hand wheel the feed rod M is driven in or out. The portion M' of the feed rod that lies within the oil pipe section E, is square in cross section in order that the feed rod may be maintained in a central position within the oil pipe. The extreme inner end of said oil feed pipe is fitted with a substantially cone-shaped head P which co-operates with the end of the oil feed pipe section E in spreading the escaping oil in a film-like sheet immediately in advance of the jets of steam escaping through the openings D in the end of the steam pipe C. The two bodies, to wit, the steam and oil meeting in this manner and at this point results in a very satisfactory mixture of fuel.

Having described my invention, I claim:

A burner of the type specified comprising a sectional oil inlet pipe, a steam inlet pipe inclosing the outlet section or discharge end of said oil inlet pipe, the discharge end of said steam pipe being contracted around the oil pipe adjacent to the discharge end thereof and the said contracted end being provided with a series of jet openings, a steam supply pipe, a coupling member uniting said steam inlet pipe and said steam supply pipe and forming a passage to the steam inlet pipe, a packing gland sealing said passage beyond the coupling member, and an oil feed rod within the sectional oil inlet pipe, said

feed rod having a conical shaped head which
coöperates with the discharge end of said
oil feed pipe in presenting the oil in an ex-
panded film-like body immediately in ad-
vance of the steam escaping from the jet
openings in the steam inlet pipe, substan-
tially as described.

In testimony whereof I affix my signature,
in presence of two witnesses.

JOHN E. LIMBACHER.
